(57) **CLAIM**

The ornamental design for a portable eBook and electronic device carrier, as shown and described.

DESCRIPTION

FIG. 1 is a perspective view of a portable eBook and electronic device carrier;

FIG. 2 is a perspective view thereof showing the addition of an eBook shown in broken lines;

FIG. 3 is a front elevational view thereof;

FIG. 4 is a rear elevational view thereof;

FIG. 5 is a bottom plan view thereof;

FIG. 6 is a top plan view thereof;

FIG. 7 is a right-side elevational view thereof; and,

FIG. 8 is a left-side elevational view thereof.

The broken line showing of an eBook is included for the purpose of illustrating environmental structure and forms no part of the claimed design.
